UNITED STATES PATENT OFFICE.

ALEXIS S. LOMSHAKOFF, OF PRAGUE, CZECHOSLOVAKIA.

FIRE GRATE.

Application filed September 19, 1923. Serial No. 663,562.

My invention relates to improvements in fire grates, and while the invention is especially applicable to the grates of stoking furnaces of various kinds, it is also useful 5 for any sort of fire grate. In stoking furnaces, and in many other furnaces, it is customary and desirable to use a very fine fuel. There is difficulty, however, in the use of this cheap fuel in that if the grate 10 is at all coarse the fuel falls through the grate and if it is fine enough to support the fuel then numerous air openings are formed and a forced draft is necessary which causes the air to issue in jets through 15 the fine holes in the grate and thus the fuel is blown away and carried off with the products of combustion, that is, with the smoke or into the ashes.

The object of my invention is to overcome 20 this difficulty and to produce a fire grate which is applicable to any furnace where a fire is used and small fuel is employed, and which has a body dense enough to support the finely divided fuel and yet 25 porous enough to permit the air to flow through it to promote combustion.

I attain this end to the best advantage by making the fire grate with a body of 30 more or less finely divided and fire-resisting material such as particles of magnesite, quartz, finely divided metal slag or the like.

It will be seen that in this way I can produce a body which will be permeable 35 to the draft of air but in which the air ducts extending through the grate body are of such irregular construction owing to the loose material that the said ducts are baffled and the air flows through evenly on all parts of the grate, thus promoting 40 excellent combustion, but in such a way as not to seriously disturb the body of finely divided fuel which lies upon the grate. Obviously this arrangement can be carried 45 out in many ways. The most natural and convenient way is to provide a frame carrying a screen which will support the loose particles forming the grate body. If desired, this body can be formed of a plurality of layers or strata of material, some 50 coarse and some fine, and it will be seen at once that by varying the size of the material the thickness of the body or the amount of compression applied to the mass, the grate can be given any desired density 55 or porosity. The form of the grate is not

essential, and this will appear more clearly from the description which follows.

Reference may be had to the accompanying drawings forming a part of this specification, in which:

Figure 1 is a plan view of a simple form of grate showing my improvement;

Figure 2 is a cross section of the structure shown in Figure 1;

Figure 3 is a cross section showing a 65 grate made up of plural layers of coarse material;

Figure 4 is a plan view of a grate having numerous cells to support the porous 70 bed;

Figure 5 is a cross section of the structure shown in Figure 4;

Figure 6 is a cross section of a cellular 75 bed having plural layers of porous material;

Figure 7 is a fragmentary section showing cells with irregular walls for supporting the material or bed of the grate;

Figure 8 is a sectional elevation, partly 80 diagrammatic, illustrating the application of the invention to a stoking furnace;

Figure 9 is a broken plan view of the grate construction shown in Figure 8; and

Figure 10 is a cross section of the structure shown in Figure 9.

In its simplest form the grate has an enclosing frame 10, shown in Figures 1 and 2 with a screen bottom 11, through which air may pass and which supports the body or bed 12 made up as above described of 90 broken particles of fire-resisting material. This bed, as above stated, can be made more or less dense and of more or less finely divided material according to the use to which it is to be put and the character of 95 the fuel to be burned thereon.

In carrying out my idea further, the upper bed 12 may have an underlying bed of coarser or less coarse material, in which case an enclosing frame 13 can be conveniently used, which has a screen bottom 14, and the underlying bed 15 rests on this screen and below the screen 11 of the upper stratum.

In Figures 4 and 5 I have shown a form 105 of bed or grate which is suitable for many purposes, but which illustrates the idea above described, and in this case the frame 16 is made up of numerous cells 17 in which is placed the material 18 comprising the 110

porous body of the bed, while the material is held in place by an underlying screen 19.

As illustrated above, this structure may also have an underlying bed 21 or more beds if necessary, and a screen bottom 20 to support it.

In Figure 7 I have illustrated still another means of carrying my invention into effect, in which cells 25 are formed with 10 irregular walls or partitions 22, which are bent as shown at 23 and with terminal flanges 24, these being spaced apart from the next adjacent partition so that the material 25 forming the body of the grate will 15 lie in the cells without the necessity of using an underlying screen.

In Figure 8 I have shown the application of my improved grate to a stoking furnace which in this instance is of a type illustrated more fully in another application for Letters Patent of the United States, which I have filed under date of September 19th, 1923, Serial No. 663,561, but while the grate forming this invention is well adapted to 25 the particular type of stoking furnace referred to, it can with equal facility be applied to any form of stoking furnace. As illustrated here, however, the grate, the body of which can be in any of the forms above described, is provided at one end with a pusher bar 26 having air ducts 27 therein formed by the tongue 28, so that the pusher bar may be detachable and bars of different sizes used. To illustrate this it will be observed that the pusher bar at the right hand of Figure 8 is higher than the one shown in the middle of the figure. These platform grates arranged in step fashion as shown, reciprocate back and forth with relation to each other and they have plane surfaces 29 near the pusher bars 26 on which the pusher bars ride, and engaging members 29^a to cooperate with some means of reciprocating the platform.

45 In Figure 8 I have also shown in a general way mechanism 30 for reciprocating the grates, but this is not referred to in detail as it is the subject of my other application hereinabove referred to.

50 From the foregoing it will be seen that the particular structures which I have here illustrated are not so important, but they

show the feasibility of making a grate embodying my invention in any form desired, and it will be noted that while the grate 55 which I have described and shown is especially adapted to the use of fine or powdered fuels, it can also be used to advantage with any ordinary fuel, as coarse coal or lignites, having finer particles which rattle 60 off in the course of consumption or otherwise.

The grate hereinbefore described with the fire resisting materials, serves successfully as the bottom of a combustion chamber in 65 cases where pulverized, liquid, or gaseous fuel is used. By the use of the grate it is possible to conduct and distribute the air so as to promote complete combustion in the combustion chamber, and also to cool any 70 particles of slag or ashes which fall on the grate. The unburnt particles of fuel falling on the grate will meet a flow of air which will either force them back to the combustion chamber, or they will burn on 75 the grate itself on top of the particles which have already been consumed or in course of consumption.

I claim:

1. A fire grate having a permanent body 80 of air permeable parts formed of strata of fire resisting particles, the strata being of varying air porosity.

2. A fire grate having a body portion formed of strata of fire resisting particles, 85 the several strata being of varying densities.

3. A fire grate having a cellular body with the cells permanently filled with fire resisting material which is permeable to air. 90

4. A fire grate having a body portion formed of strata of fire resisting particles with the particles of one stratum of a general size different from that of an adjacent stratum. 95

5. A fire grate comprising a cellular body having the cells thereof permanently filled with material which fuses only at exceedingly high temperatures and which is permeable to air. 100

In testimony whereof, I have signed my name to this specification this 17th day of September, 1923.

ALEXIS S. LOMSHAKOFF.
